CLAIM

We claim the ornamental design for a powered tape dispenser, as shown and described.

DESCRIPTION

FIG. 1 is a perspective view of the powered tape dispenser showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof; and,

FIG. 7 is a rear elevational view thereof.

The indicia depicted by means of broken lines in FIGS. 1 and 4 has been shown for illustrative purposes only and forms no part of the claimed design.
